UNITED STATES PATENT OFFICE

HELEN UFFORD, OF NEW YORK, N. Y., ASSIGNOR TO QUAKER OATS COMPANY, OF CHICAGO, ILLINOIS, A CORPORATION OF NEW JERSEY

DESIGN FOR A PLATE OR SIMILAR ARTICLE

Application filed June 28, 1930. Serial No. 36,215. Term of patent 7 years.

To all whom it may concern:

Be it known that I, HELEN UFFORD, a citizen of the United States, and resident of the borough of Manhattan, city, county, and State of New York, have invented a new, original, and ornamental Design for a Plate or Similar Article, of which the following is a specification, reference being had to the accompanying drawing, forming part hereof, which drawing is a face view of a plate showing my new design.

I claim:

The ornamental design for a plate or similar article, as shown.

HELEN UFFORD.
